(57) **CLAIM**

The ornamental design for a tray, as shown and described.

DESCRIPTION

FIG. 1 is a perspective view of a tray showing my new design.

FIG. 2 is a left elevation view of the tray of FIG. 1, the right elevation view is a mirror image.

FIG. 3 is a front elevation view of the tray of FIG. 1, the rear elevation view is a mirror image.

FIG. 4 is a top plan view of the tray of FIG. 1.

FIG. 5 is a bottom plan view of the tray of FIG. 1; and, FIG. 6 is a plan view of the tray of FIG. 1 in an unfolded configuration.

The broken lines are shown for the purpose of illustrating parts of the article which form no part of the claimed design.
